(57) **CLAIM**

The ornamental design for an access needle securement device, substantially as shown and described.

DESCRIPTION

FIG. 1 is a top isometric view of an access needle securement device;

FIG. 2 is a top plan view thereof;

FIG. 3 is a front elevation view thereof;

FIG. 4 is a right side view thereof;

FIG. 5 is a left side view thereof;

FIG. 6 is a rear view thereof; and,

FIG. 7 is a bottom plan view thereof.

The broken lines in the figures illustrate environmental structures and portions of the design that form no part of the claimed design.
